JOHN L. WAIT, OF EAST CAMBRIDGE, ASSIGNOR TO HIMSELF AND GEORGE J. SUTTON, OF CAMBRIDGEPORT, MASSACHUSETTS.

Letters Patent No. 78,033, dated May 19, 1868.

IMPROVEMENT IN COMPOSING-STICKS.

The Schedule referred to in these Letters Patent and making part of the same.

TO ALL PERSONS TO WHOM THESE PRESENTS MAY COME:

Be it known that I JOHN L. WAIT, of East Cambridge, in the county of Middlesex, and State of Massachusetts, have made a new and useful invention having reference to Composing-Sticks for the Use of Type-Setters; and I do hereby declare the same to be fully described in the following specification, and represented in the accompanying drawings, of which—

Figure 1 is a top view,

Figure 2 a transverse section, and

Figure 3 a rear elevation of a composing-stick provided with my invention.

Figure 4 is a front view of its adjustable shoulder and its clamp.

In such drawings, A denotes a composing-stick of the usual form, *a* being its abutment, and *b* its type-supporting ledge.

B is the adjustable shoulder or slide, which is placed against the ledge *b*. Instead of making the ledge with one or more holes or slots to receive one or more screws to confine the shoulder *B* in place, as it is customary to make, I provide such shoulder with a clamp, *C*, to straddle or clasp the ledge in manner as represented.

From the rear part of the clamp a pin, *D*, extends, and goes through the base part *a'* of the shoulder *B*, and also through a washer, *b'*, and is jointed to a cammed lever, *E*, which is formed and arranged in manner as represented.

The base of the shoulder is recessed, as shown at *c*, to receive the rear portion of the clamp, and below the cammed lever a screw, *d*, is screwed through the base of the shoulder, and against the lower part of the back portion of the clamp.

By means of the screw, the clamp may be adjusted, so as to cause the cammed lever to act with a greater or less degree of power on the clamp, as occasion may require, in order to confine the shoulder to the ledge of the composing-stick.

The ledges of different composing-sticks vary in their thickness. As one shoulder will answer for several of such sticks, it becomes desirable to have the clamp applicable to either, whatever may be the thickness of its ledge. The screw enables this to be accomplished, and the cammed lever be caused to act with the requisite pressure. By turning the cammed lever into parallelism with the ledge, the shoulder will be clamped to the ledge. Thus, by means of the clamp applied to the ledge, in manner as explained, and by the cammed lever jointed to the pin *D*, the shoulder, when adjusted at any desirable distance from the abutment, may be there fixed.

I claim as my invention, the clamp *C*, as combined with the cammed lever *E* and the adjustable shoulder *B*, and formed to straddle or embrace opposite sides of the ledge of the composing-stick.

I also claim the combination and arrangement of the screw *d* with the clamp *C*, the cammed lever *E*, and the adjustable shoulder *B*, arranged and applied together, substantially in manner and so as to operate as specified.

J. L. WAIT.
